UNITED STATES PATENT OFFICE.

STANLEY B. HOLMES, OF SEATTLE, WASHINGTON.

CARBURETOR.

Application filed April 9, 1923. Serial No. 630,785.

This invention relates to improvements in carburetors, and has for its principal object to provide a carburetor into which gasoline may be fed from a supply tank at a lower level by means of sub-atmospheric pressure.

Another object of the invention resides in the provision of means whereby the connection with the sub-atmospheric pressure is automatically controlled to maintain the supply within the carburetor.

A further object is to provide a carburetor wherein there is an automatic regulation of air admitted to the mixing chamber in proportion to the amount of gasoline consumed.

Other objects reside in the provision of means for effectively vaporizing and mixing the fuel before it passes into the manifold.

In accomplishing these and other objects of the invention, I have provided the improved details of construction, the preferred forms of which are illustrated in the accompanying drawings, wherein—

Figure 1 is a side view of a carburetor constructed in accordance with the present invention.

Figure 2 is an enlarged, sectional view of the same.

Figure 3 is a detail, sectional view of the float actuated valve mechanism for controlling the vacuum pressure in the float chamber.

Referring more in detail to the several views of the drawings wherein like reference numerals designate the same, or like parts.

1 designates, as a whole, a carburetor constructed in accordance with the present invention, and comprising a vertical, tubular portion 2 provided with a flange 3 at its upper end through which bolts, as at 4, are extended to secure the device to the fuel intake manifold of an engine. Cast integrally with the tube, at one side and near its lower end is a bowl forming a supply chamber 5, and fitted within the upper portion of this bowl is a cup which forms a float chamber 6 and over which a cover plate 7 is fitted and secured to the bowl by screws 8 to tightly close both against leakage. Extended forwardly from the base of float chamber and threaded into a boss 9 in base of bowl 5 is a tube 10 by which connection is made with a supply tube 11 that may lead from a source of supply at a lower level than the carburetor. The tube 10 has a lat-

eral extension 12 wherein is an upwardly directed opening 13 into the bowl; this opening being normally covered by a valve plate 14 mounted on guide pins 15 which will rise to permit a flow into the chamber 5, but will automatically close to prevent any back-flow.

The flow of gasoline from conduit 11 is automatically controlled by the action of a float 16 located in chamber 6 and slideable on a valve pin 17 extended centrally therethrough and downwardly through tube 10; it being provided with a tapered lower end 18 adapted to a tapered valve seat 19. The top of the float is engaged by the outer ends of weighted levers 20 supported pivotally, as at 21, from the cover 7 and having operative connection at their inner ends with the pin 17 in such manner that lowering of the float will raise the pin to permit an inflow of gasoline, and rising of the float will move the pin toward closed position to cut off the inflow.

The tube 2 is open at its lower ends to provide an air intake passage 24 directly into the manifold, and fitted within this passage in spaced relation are rings 25 and 26 each tapered from its opposite sides to the central passage so as to form Venturi tubes, and beneath these are valves 27 and 28 of the butterfly type operable respectively by means of levers 29 and 30 on the outer side of tube 2.

Formed in the ring 25 is an annular passage 31 which is connected through a lateral opening 32 in the tube wall with a tube 33 that leads downwardly through an opening 34 in the cover plate 7 and to a point near the bottom of a well 35 formed in the bowl; the well being fed from chamber 5 through a small port 36 in the bottom of the well. From the passage 31 a plurality of small outlets 37 lead into the Venturi opening just above its most restricted part.

Likewise, in the ring 26 upper and lower annular passages 40 and 41 are formed from which outlets 42 and 43 lead into the Venturi opening in alternating relation just above the most restricted part of the passage. Passage 41 is connected by means of a passage 44 with the bottom of supply chamber 5, and passage 40 is fed by means of a passage 45 that opens into the base of the well 35. To permit a ready rise and fall of gasoline in chamber 5, and well 35, the former is provided through cover plate 7,

with an air inlet 46 while air may enter the well through the opening 34 which is made larger than necessary to receive pipe 33.

Connected with the tube 2 above the ring 5 25 is a pipe 50, having its lower end opening into the side of a dome 51 that is mounted on the cover plate 7 and into which the upper end of pin 17 extends, and slidably fitted within the dome is a sleeve valve 52 10 that may be moved upwardly to close the end of pipe 50, or downwardly to cover an opening 53 to atmosphere in the opposite side of the dome and offset from the opening into pipe 50; the movement of the sleeve 15 being limited by stops 54 and 55. The sleeve is actuated by connection with the pin 17, the connection comprising a pair of levers 56 pivotally connected at their inner ends with a plate 57 mounted between adjusting 20 nuts 58 on the pin and with their outer ends extended between flanges 59 on the interior of the sleeve. A tensioned spring 60 connects the arms so as to throw them quickly in opposite directions when actuated from 25 one side to the other. With the parts as shown in Figure 3, the float chamber is connected with the sub-atmospheric pressure in the manifold and gasoline may be drawn into the chamber, but when the chamber is 30 filled, the float will rise and cause pin 17 to be moved downwardly. This will cause the pivoted inner ends of levers 56 to be moved past the dead center line and spring 60 to snap them upwardly to throw the 35 valve sleeve upwardly to close pipe 50 and uncover the opening 53, thereby shutting off the sub-atmospheric pressure and allowing air to enter the chamber through port 53, so that the gasoline may flow out as needed 40 through passage 13 into chamber 5.

With the parts so constructed and assembled, operation would be as follows:

On starting the engine to which the carburetor is attached, valve 28 would be closed 45 while valve 27 is left open. Suction in the manifold then causes gasoline to be drawn into the mixing passage 24 through passages 44 and 45, giving a rich mixture for starting. As soon as the engine has been started, 50 valve 28 should be opened to permit an intake of more air and thereby decrease the suction through the gasoline passages, thus giving a leaner mixture.

While the engine is idling, valve 27 should 55 be nearly closed. This will cause gasoline to be fed from well 35 through tube 33 and delivered into the mixing passage through ports 37 whereby it is finely vaporized and mixed with air so that a very small amount 60 of gasoline is necessary.

While driving the vehicle, valve 27 is

opened and the speed controlled by its adjustment between opened and closed positions. It will be seen that gas will be taken in through passages 44 and 45, and since the 65 hole 36 in bottom of well 35 is very small, the well will soon be emptied and then air will be admitted through the well and passage 45, and into the mixing tube through ports 42. In this way the amount 70 of gasoline needed is automatically regulated. With a carburetor of this character there is a better mixing of fuel and air than is ordinarily possible, since the two Venturi tubes and the small ports opening into the 75 same effect this result.

Having thus described my invention, what I claim as new therein and desire to secure by Letters Patent, is:

1. In a carburetor, in combination with a 80 suction manifold, a float chamber, a fuel storage chamber adapted to be filled through a back check valve connection with the float chamber and having connection with a source of fuel supply, a valve in said fuel 85 supply connection, a float for controlling said valve, a cylindrical dome opening into the top of the float chamber and having an opening in the side thereof to outside atmosphere, a suction conduit from the suction manifold opening into one side of the dome in offset relation above the opening to atmosphere, a sleeve slidably fitted in the dome and operable by the float between positions to cover either the opening to atmosphere or the opening to the suction manifold. 95

2. In a carburetor, in combination with a suction manifold, a float chamber, a float in the said chamber, a fuel storage chamber adapted to be filled through a back check 100 valve connection with the float chamber and having connection with a source of fuel supply, a valve stem adapted to be actuated by the float to open or closed connection with said source of supply, a cylindrical dome opening 105 into the top of the float chamber and having an opening in the side thereof to outside atmosphere, a suction conduit from the suction manifold opening into one side of the dome in offset relation above the opening to atmosphere and a sleeve slidably fitted 110 in the dome and movable to separately cover either the opening to atmosphere or to the suction manifold, stops in the dome for limiting the sleeve movement, yieldable trip 115 members for shifting the sleeve from one position to another, and means connected with the valve pin for actuating the trip members.

Signed at Seattle, King County, Washington this 3rd day of April, 1923.

STANLEY B. HOLMES.
